UNITED STATES PATENT OFFICE.

EMILE GIRAUD, OF PARIS, FRANCE.

SAFETY DEVICE FOR OVERHEAD ELECTRIC CONDUCTORS.

No. 826,845.

Specification of Letters Patent.

Patented July 24, 1906.

Application filed April 10, 1905. Serial No. 254,836.

To all whom it may concern:

Be it known that I, EMILE GIRAUD, engineer, a citizen of the French Republic, residing at Paris, France, have invented certain new and useful Improvements in Safety Devices for Overhead Electric Conductors, of which the following is a specification.

This invention has for its object to provide means whereby in case of a high-voltage overhead conductor breaking the same is connected to earth or short-circuited by another conductor in its vicinity.

In the accompanying drawings, Figures 1, 2, and 3 represent in elevation, side view, and plan, respectively, a safety arrangement constructed according to this invention; Fig. 4, a side view, and Fig. 5 a section, of a modification of a detail. Fig. 6 shows the line in its normal state, and Fig. 7 shows the line with the conductor *e* broken.

Referring to Figs. 1, 2, and 3, in the groove formed in the head of the insulator *b* is placed a trough-shaped metal piece *a* for the reception of the conductor *e*, the said metal piece *a* having two extensions *c* and *c'*, provided with pins *d* and *d'*. The conductor *e*, laid in the trough *a*, can slide therein. On the pins *d* *d'* are pivoted two forked pieces *f* *f'*, which bear on the conductor *e*, each fork-piece carrying a light and rigid extension *g*, consisting of a tube preferably of aluminium and terminating in or carrying at its end and at right angles thereto a tube *h* *h'* of U-shape or bent to the shape of an arc. On the conductor *e* are fixedly mounted rings *i* *i'*, having upwardly-extending members *j* and *j'*, which, in the event of the conductor breaking, the consequent traction exerted on the portion of the conductor that is not broken is caused to bring either of said members *j* and *j'* to bear against the forked pieces *f* or *f'*, as the case may be. These forks under the pull exerted by the sleeves *i* or *i'*, having the members *j* and *j'*, are tilted, thereby causing the part *h* or *h'* of the arm *g* or *g'* to come in contact with one of the other conductors arranged in the vicinity of the first conductor.

It will be observed in Figs. 6 and 7 that there are two conductors *e* and *e'*. For the conductor *e* the safety devices are disposed for coming into contact with the conductor *e'* if the conductor *e* breaks. For the conductor *e'* the safety devices are disposed for coming into contact with the conductor *e* if the conductor *e'* breaks. *n* is the dynamo, and *o* a circuit-breaker which cuts out the

current when a short circuit is established between the two conductors.

In the case of a single conductor the same arrangement permits of connecting the conductor to earth.

To the rings *i* and *i'* are pivoted forks *j* and *j'*, embracing the extensions *g* *g'*. These forks are intended to engage and support the arms *g* and *g'* and also to prevent said arms *g* and *g'* from tilting too far in an upward direction, when, as would be the case in certain position, gravity would tend to bring the arms *g* and *g'* away from the conductor.

This apparatus need not be provided on all the posts of the line, as it will suffice to provide it on every second or third post, the intermediate posts being provided with simply trough-shaped pieces fixed to the top of the insulator to carry the conductor *e*.

The trough-shaped piece *a*, carrying the pins *d* *d'*, may be constructed in various manners. It may, for instance, be cast in one piece with the extensions *c* *c'* and with the arms *k* *k'*, by which it is fixed to the insulator *b*. It is necessary in this case to have as many patterns as there are types of insulators and arrangements of the conductors one relatively to the other.

The trough-shaped member may be constructed as shown in Figs. 4 and 5. It consists of a central tubular member *a* with two fastening-arms *k* *k'*. The tubular member *a* is provided at each end with flutings, in which collars *m*, provided with projections *n*, corresponding to the flutings, may be fixed in variable directions. The pins *d* are carried by the collars *m*. This modified arrangement requires as many patterns as there are types of insulators.

Having now particularly described and ascertained the nature of my said invention and in what manner the same is to be performed, I declare that what I claim is—

1. In a safety device for overhead electric conductors, an insulator having a groove, a trough-shaped metal piece mounted in the groove for supporting the conductor, a jointed fork arranged on each side of the trough and embracing the conductor and terminating in an arm, a U-shaped piece supported by the latter, a ring fixed to the conductor on each side of the insulator and beyond the forks and having a diameter sufficient to prevent the said rings passing between the branches of the corresponding fork, substantially as described.

2. In a safety device, an insulator, a trough-shaped member formed of a single piece mounted in said insulator and having extensions, forks carried by the extensions and 5 having branch arms for engagement with the conductors, substantially as described.

3. In a safety device of the class described, an insulator, a trough-shaped member supported by said insulator for receiving the 10 conductor, extensions on said member, forks having arms pivotally connected to said extensions, and means carried by the conductor for actuating the arms, substantially as described.

4. In a device of the class described, a conductor-support, tilting members connected to said support and having arched-shaped terminals, and means on the conductor at opposite sides of the said support for engagement with said members for tilting the same when 15 said conductor is severed.

In testimony whereof I have hereunto set my hand in presence of two subscribing witnesses.

EMILE GIRAUD.
